CLAIM

The ornamental design for a slide-out camera platform as shown and described.

DESCRIPTION

FIG. 1 is a front, top, and left perspective view of a slide-out camera platform showing my new design; FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right perspective view thereof; and,

FIG. 9 is an enlarged view of the portion indicated with the number 9 in FIG. 1.

The broken lines shown in the drawings represent portions of the slide-out camera platform that form no part of the claimed design. The dot-dash broken lines encircling an enlargement portion of the design forms no part of the claimed design.

1 Claim, 9 Drawing Sheets
